(57) **CLAIM**

The ornamental design for a display screen or portion thereof with animated graphical user interface, as shown and described.

DESCRIPTION

FIG. 1 is a front view of a display screen or portion thereof with animated graphical user interface showing a first embodiment of the claimed design;

FIG. 2 is a front view showing a second image of the first embodiment;

FIG. 3 is a front view showing a second embodiment of the claimed design;

FIG. 4 is a front view showing a second image of the second embodiment; and,

FIG. 5 is a front view showing a third image of the second embodiment.

The appearance of the transition is sequential from FIG. 1 to FIG. 2 and from FIG. 3 to FIG. 5. The process or period in which an image transitions to another image forms no part of the claimed design.

The shading indicates a contrast in appearance.

The longer broken-line showing of a portion of an electronic device and the shorter broken-line showing of a display screen boundary, are included for the purpose of illustrating environmental structure and form no part of the claimed design.
